UNITED STATES PATENT OFFICE.

CARL F. RAKOW, OF WHEATLAND, NORTH DAKOTA.

CAR-DOOR LOCK.

1,151,392.

Specification of Letters Patent. Patented Aug. 24, 1915.

Application filed November 13, 1914. Serial No. 871,971.

To all whom it may concern:

Be it known that I, CARL F. RAKOW, a citizen of the United States, residing at Wheatland, in the county of Cass and State 5 of North Dakota, have invented certain new and useful Improvements in Car-Door Locks, of which the following is a specification.

My invention relates to new and useful 10 improvements in car doors and more particularly to locking means therefor which forms a part of my pending application for patent filed Feb. 12, 1914, Serial #818,203 and has for its primary object to provide a 15 simple, extremely useful and inexpensive lock that will effectively lock car doors in closed position so that leakage of grain or accidental derangement of the doors is prevented.

20 An important object of my invention is to provide a lock of the character described which consists of vertical slidable bars that are mounted upon a car door and carry locking tongues that are arranged to fit within 25 recesses in the sides of the door frame, said locking tongues being provided with independent locking means and said bars being operable by a novel form of operating means.

30 Another important object of my invention is to provide a lock of the character described which is simple as to construction, reliable and efficient in operation and inexpensive to manufacture and install.

35 The above and additional objects are accomplished by such means as are illustrated in the accompanying drawings, described in the following specification and then more particularly pointed out as claimed.

40 With reference to the drawings, wherein I have illustrated the preferred embodiment of my invention as it is reduced to practice, and throughout the several views of which similar reference numerals designate corresponding parts: Figure 1 is a fragmentary front elevation showing my improved locking means in locked position and attached to a car door consisting of two door sections, Fig. 2 is a longitudinal fragmentary 45 sectional view taken through one of the door sections, Fig. 3 is a vertical sectional view taken through the lower door section, and Fig. 4 is a detail perspective view of the operating handle for the locking means.

55 Referring to the drawings by characters

of reference the numeral 1 designates as an entirety a door frame of a car in which is mounted a door forming the subject matter of my pending application, Serial #818,203 which consists of two sections arranged one 60 above the other and designated respectively 2 and 3.

My improved locking means comprises vertical bars horizontally slidable 4 and 5 that are mounted upon the outside faces of 65 the door sections 2 and 3 and each bar has secured thereto adjacent the ends thereof locking plates 6 and 7. The bars 4 and 5 serve as connecting mediums for the members 6 and 7 and are supported thereby. 70 Each of the locking plates is secured intermediate its ends transversely of the bars 4 and 5 so as to provide projecting locking tongues 9 that extend outwardly from the bars and are designed to fit within the recesses 10 formed in the door frame 1. The plates 6 and 7 are inwardly offset as at 11 and extend inwardly from the bars 4 and 5 toward the center of the door in engagement with the outer faces of the door sections. 80 The plates in being offset fit snugly about the inner longitudinal edges of the bars 4 and 5.

The inwardly extending portions of the plates 6 and 7 are designated 12 and are 85 slidable through angular guides plates 13 that are secured upon the outer faces of the door sections and arranged longitudinally thereof in pairs, each plate of a pair spaced at its inner longitudinal edge from the other 90 plate of the pair. Corrugations 13' are formed upon the outer faces of the portions 12 of the plates, said portions 12 being longitudinally slotted.

Screw threaded bolts 14 in the door are 95 inserted through the space between the inner edges of the plates 13 of the door sections 2 and 3 and the slots in the corrugated portions 13'. The outer end of each bolt is enlarged to provide a flange or head 15 so 100 as to prevent removal of the locking lever 16 which is turned and adjustably mounted upon each bolt. An elongated corrugated plate 17 is mounted upon each bolt 14 between the locking lever 16 and corrugated 105 faces 13 of the plates 6 and 7.

It will be readily seen that when the locking lever 16 is turned to bring the corrugated plates 17 into coöperating engagement with the corrugated surface of each of the 110

plates 6 and 7 the locking plate will be held in rigid locked position and subsequently the tongues 9.

As a means for sliding the bars 4 and 5 so that the tongues 9 move into the recesses 10 I provide in connection with each door section a horizontal operating shaft 19 that is journaled in the bearing member 20 arranged centrally of the ends of each section. The operating shaft 19 is provided with screw threads 21 at each end, said screw threads being arranged in opposite directions. Carried centrally of the ends of each of the bars 4 and 5 is an approximately U-shaped operating rod receiving member 22 which is provided centrally of its ends with an approximately cylindrical enlarged and internally screw threaded portion 23. The members 22 are secured at their ends by bolts 20 or other suitable fastening means 24. The portions 23 receive the screw threaded ends 21 of the operating shafts 19.

Formed upon the shaft 19 upon opposite sides of the bearing member 20 are angular 25 enlarged wrench fitting portions 25 and 26. When the shaft is rotated the bars 4 and 5 are moved according to the direction of the rotation of the shaft so as to bring about the locking or unlocking action, it being necessary of course to unlock the individual locking means for the plates 6 and 7.

The door sections are similar to the ones described and illustrated in my pending application for patent, Serial #818,203 and 35 are supported swingingly by hangers 29 and 30 that are carefully described and illustrated in the above mentioned application.

With reference to the foregoing description and accompanying drawings it will be 40 readily seen that I have provided a simple and inexpensive car door lock which may be readily operated so as to effectively lock car doors and is cheap to manufacture.

In practice, I have found that the form 45 of my invention, illustrated in the drawings and referred to in the above description, as the preferred embodiment, is the most efficient and practical; yet realizing that the conditions concurrent with the adoption of 50 my device will necessarily vary, I desire to emphasize the fact that various minor changes in details of construction, proportion and arrangement of parts may be resorted to, when required, without sacrificing 55 any of the advantages of my invention, as set forth.

What is claimed is:—

1. In a car door lock, the combination with a door of locking plates slidable upon 60 the doors adjacent the ends thereof, bars connecting certain of the locking plates with each other and slidable upon the door,

means to slide said bars to move said locking plates into and out of locking position and means to independently lock the locking 65 plates in locked position operating in connection with the inner ends of each plate.

2. The combination with a car door of locking means therefor, comprising vertical slidable bars, locking plates secured at 70 the ends of the bars transversely thereof and projecting outwardly from the bars on either side thereof, a horizontal rotary shaft operatively connected at its ends with said bars, means to rotate said shaft to move said 75 bars back and forth, said outer extended portions of the locking plates arranged to extend within recesses in the frame of the door, guide plates slidably receiving the inner ends of the locking plates and means 80 to lock each of the locking plates in locked position.

3. In a car door lock, the combination with a door, of means for locking said door in closed position comprising locking plates 85 slidably mounted at the ends of the door and having the outer faces of their inner ends corrugated, guide means upon the door to slidably receive the inner corrugated ends of the locking plates, corrugated plates carried upon the door, means for forcing said corrugated plates into locking engagement 90 with the corrugated inner ends of the locking plates and means for moving said locking plates into and out of locking engagement with the door frame. 95

4. In a car door lock the combination with a door of means for locking said door in closed position comprising bars vertically 100 and slidably mounted upon said door, locking plates mounted upon said bars in pairs, said plates arranged to extend for a portion of their length within recesses of the door frame of the car, said plates having their inner ends formed with a corrugated outer 105 surface, guide plates for said locking plates, said corrugated portions of the locking plates being longitudinally slotted, bolts extending through the slots and carried by said door, a locking lever adjustably mounted upon each of said bolts, a corrugated plate loosely mounted upon each of said bolts and arranged to be moved into and out of locking engagement with the corrugated surface of said locking plates and 110 means for moving said locking plates into and out of locking position operatively connected with said vertical bars. 115

In testimony whereof I affix my signature in presence of two witnesses.

CARL F. RAKOW.
